WATCHMAN'S ELECTRIC CLOCK

Filed May 25, 1927

Samuel B. Chapman
Attorney

UNITED STATES PATENT OFFICE

SAMUEL B. CHAPMAN, OF BALTIMORE, MARYLAND

WATCHMAN'S ELECTRIC CLOCK

Application filed May 25, 1927. Serial No. 194,165.

This invention relates to watchmen's clocks for recording the movements of a watchman in his rounds from one place to another at certain regular or prescribed intervals, or to record the activity or alertness of the watch aboard ship.

The essential objects of the invention are to provide an electrically controlled apparatus of the class specified wherein is embodied a novel and compact arrangement of instrumentalities for reliably recording, through circuit closing means operably associated with a clock and a specially arranged rotatable dial disk attached thereto, the time of inspection or watchful service of a watchman by actuation of the circuit closing means located at different prearranged posts or stations in a manufacturing plant or factory, building compartments or aboard ship; to indicate with certainty and accuracy the time that reports are made from independent stations included in the installation; and further, to prevent all possibility of an irregular or incorrect record by providing a recording structure and arrangement of such nature as to defeat all attempts to change the mechanism from a regular or normal condition of operation.

With the foregoing and other objects and advantages in view, the invention consists in the preferred construction and arrangement of the several parts more fully described and claimed.

In the drawing:

Figure 1 is a front elevation of a watchman's clock embodying the features of the invention, and showing the electrical connections and wiring in diagram.

Figure 2 is a horizontal section taken in the plane of line 2-2 of Figure 1, with the upper vibrator organization broken off and the electric wiring removed.

Figure 3 is a top plan view of an improved form of dial organization used in connection with the improved watchman's clock.

Figure 4 is a front elevation of the dial member which receives the record and which replaces the ordinary minute and hour hands of the clock.

Figures 5 and 6 are respectively a top plan view and a side elevation of one of the recording vibrating heads connected to and operated by a vibrator.

In the accompanying drawing, a certain arrangement of the several instrumentalities is illustrated for the purpose of compactness, and therewith is shown, in diagram, the source of electrical energy and the electrical connections and a specific grouping of the prime operating means or push buttons, but it will be understood that the invention is not confined to this particular arrangement of the several parts, but may be varied in accordance with the application of improved watchman's clock without in the least departing from the essential features of the invention.

As shown, the improved structure comprises a base 5 and thereon is held a support 6 at one side and an upright 7 at the opposite side. On the support a clock 8 of ordinary form is held in fixed position and from the arbor 9 of which the ordinary hour and minute hands are removed and replaced by a special dial organization, including an inner stationary metal disc 10, a rubber or yielding cushion disc 11, a record receiving dial 12, a carbon paper disc 13 and an outer paper impression disc 14. The discs are secured to a central sleeve or tubular attaching means 15 which is slipped over the arbor of the clock to replace the ordinary hour and minute hands, the entire group of discs being secured for unitary rotation, and to the disc 10, which may serve as the backing, are attached forwardly projecting studs or keepers 16 arranged at equal distances on opposite sides of the center in diametrical alignment and inserted through openings in all of the discs and in transverse alignment, as at 17. The discs 12, 13 and 14 are removably held in connection with the metal disc 11, suitable clips 18 being removably applied over the edges of all of the said discs. The dial disc proper, indicated by 12, may be replaced at any time it may be found necessary by a similar device; it being understood that a number of these dial discs will be furnished with each

apparatus, and likewise when the outer impression disc 14 and carbon disc 13 becomes worn, they likewise may be replaced by similar devices.

On the upright 7 a series of ledge or shelf brackets 19, 20, 21 and 22 are secured and held, the said shelf brackets being disposed at different angles relatively to each other in a vertical direction and having their supports arranged as may be found necessary to serve the purposes of stability and firmness in application. There are but four of these ledge or shelf brackets shown in the present instance, and they are disposed close to the clock 8, but it will be understood that the number of these ledge or shelf brackets may be increased as found desirable and arranged at angles other than those shown, or in any manner adapted to serve the purpose of an accurate recording operation of the devices held thereby. On each ledge or shelf bracket is secured an ordinary electro-magnetic vibrator 23, comprising the usual coils or magnets 24 and vibratory member 25 functioning as an armature relatively to the magnets of said coils. The vibrating member or armature 25 of each electro-magnetic vibrator, has an arm 26 extending therefrom and preferably forming a part thereof, the said arm corresponding to the bell arm usually embodied in the ordinary construction of vibrators. In this instance, however, each arm 26 is shown bent at a point in the length thereof to enable the disposition in vertical alignment of a series of vibrating heads 27 in the form of metal blocks of sufficient weight, and each carrying on its inner side a type member or face 28, all of these type members or faces being in vertical alignment, and as shown, the said heads are all located above the horizontal center of the outer disc 14.

The dial organization, as shown, may be enlarged as a unit, as desired, and the principal member or element thereof is the dial or disc 12 which receives the record, and said dial or disc is divided into a series of segmental divisions or sections 29 by radial lines 30 and corresponding in dimensions to the five minute divisions of an ordinary clock dial, said segmental sections 29 regularly diminishing in width by reason of the inward convergence of the radial lines 30. The said sections 29 are divided by circular lines 31 concentrically around the entire record receiving dial 12, the latter dial having a circularly enclosed blank space 32 at the center, and therein are formed the two openings 33 for the purpose heretofore explained. The lines 31 divide each section 29 into spaces 34 in positions for reception of the records produced by the types of the aligned vibrating heads 27. There are four arcuate spaces 34 defined in each section 29 by the circular lines 31 to correspond to the number of heads 27

shown in the present instance, but it will be understood that the diameter of the receiving dial 12 may be increased as desired and provided with a greater number of circular division lines 31 to correspond to an increase in number of the heads 27. The hour numerals on the rim of this receiving dial 12 are reversed in accordance with the ordinary arrangement of said numerals of the clock dial, the numerals 1, 2, 3, 4, etc., being to the left of the upper central numeral 12. The same arrangement will be effected with either the ordinary or Roman numerals, so that as the dial rotates to the right or clockwise the earlier hours will be successively brought into position for engagement for receiving the records of the heads 27 therein with accuracy as to the time that said records are made by the actuation of the heads 27, and may be either at five minutes past twelve, five minutes past one, five minutes past two, etc., without stopping the clock mechanism which, if affected, would be an indication of irregular manipulation of the apparatus. It will be impossible for a watchman to turn the dial 12 and the parts cooperating therewith in a direction reverse to the direction of its normal rotation towards the right, and thus a further obstruction will be provided against irregular operation of the records, or tampering of the record, so as to overcome any attempts of a watchman to "make-up" false records that may be desired to cover up deficiencies or laxity in regular predetermined periods at which watchful inspection should be made and regular report thereof rendered by the vibratory operation of the heads 27 and a record of the posts or stations visited as represented by the numerals or other indicia 28 carried by the heads 27. The outer impression disc 14 consists of a circular sheet of blank paper and rests against the outer side of the carbon disk 13, the latter having transferring contact with the dial 12. The rubber or elastic disc 11 cushions the outer discs, which are preferably of paper, and materially assist in the formation of a legible record on the dial 12. The metal disc 10 provides a resisting backing which will form an advantageous support for the outer discs and also serve to hold the studs or keeper 16 in reliable association with the disc organization, and further by means of said metal disc 10 the entire disc organization as a unit may be more effectively secured to the outer end of the sleeve 15.

The prime operating means, directly operated by the watchman, consists of a series of push buttons or circuit closing devices 35 which may be arranged as desired at the different stations, posts or in different compartments or rooms, and as shown there are only four of these push buttons or circuit closers corresponding to the number of vi-

bratory heads 27. These push buttons are of the ordinary construction of devices of this class and are connected up by wiring, as at 33 and 34, with one side of a battery, the latter being connected, as shown, in a well known manner to effectually render the vibrators individually active when either one of the push buttons or circuit closers is actuated by a watchman. These push buttons 32 are also connected by wires 35, 36, 37 and 38 and are respectively secured to each of the vibrators and individually secured to a binding post 39 of each vibrator, as shown in diagram. The vibrators each 15 also have a binding post 40 and connection is made thereto through a wire 41 and branch wires 42 to the other side of the battery so as to complete the circuit in accordance with well known vibrator installations. It will be understood that the binding posts 39 and 40 will be respectively electrically connected to the windings of the coils of the electro-magnets 24. It will also be understood that each push button 32 will 20 individually operate or render active the vibrator controlling the actuation of the head 27 with which it may be selectively and electrically associated, the push buttons being numbered similarly to the heads 27 which 25 are arranged to be individually operated thereby.

From the foregoing, the operation of the improved device will be readily understood, and the vibrators and heads 27, together with the block and the dial organization embodying the several discs heretofore explained, may be enclosed, as desired, thus rendering them accessible to authorized persons only. Moreover, the recording dial organization and heads 27 with their operating means may be located at some predetermined point, as for instance, in an office enclosure, with the heads 27 operable at a considerable distance from the location of 40 the present apparatus, which comprises in its organization stock elements readily procurable in the market, as for instance, the vibrators, push buttons, batteries and clock. The clock may be of any suitable type from 45 which the ordinary dial can be removed and replaced by the present improved dial organization. The vibrating armatures 25, together with the arms 26 and the heads 27, may be formed integrally and of sufficient 50 dimensions to insure strength and durability and certainty of operation, it being obvious that if the heads 27 have a certain amount of weight they will produce a superior impression and record through the medium 55 of the disc 14 and the carbon paper disc 13 on the record receiving dial 12.

It is also intended to adopt such minor changes in the details of construction and arrangement of the several parts as may 60 be justified by the scope of the invention

as heretofore disclosed and pointed out in the claim.

What is claimed as new is:—

In a watchman's clock, the combination of a base, a support carried thereby, an upright 70 also carried by the base and adjacent to the support, a clock mounted upon the support, a recorder dial attached to and carried by the hour hand arbor of the clock, a plurality of angularly disposed shelves carried by the upright, a plurality of vibrator arms, one 75 to each shelf supported by the shelves with their free ends radially aligned and in spaced relation adjacent the face of the dial, recording indicia carried by the free end of each arm, and a plurality of electromagnets carried by the shelves one to each shelf and each arm, and in influencing relation to the respective vibrating arms.

In testimony whereof I have hereunto set 85 my hand.

SAMUEL B. CHAPMAN.
